(57) **CLAIM**

The ornamental design for a leaf guard, as shown and described.

DESCRIPTION

FIG. 1 is a top perspective view of a leaf guard embodying my new design;

FIG. 2 is a top plan view of the leaf guard of FIG. 1;

FIG. 3 is a rear elevation view of the leaf guard of FIG. 1;

FIG. 4 is a side elevation view of the leaf guard of FIG. 1; and,

FIG. 6 is a bottom plan view of the leaf guard of FIG. 1.

The broken line representations of items in the figures are for the purpose of illustration only, and form no part of the claimed design. The broken line representation shown in the area that is broken away is for the purpose of illustrating that a particular length of leaf guard is being claimed.
